UNITED STATES PATENT OFFICE.

JAMES BAYARD CLARK, OF NEW YORK, N. Y., ASSIGNOR TO ARCHIBALD WILSON
MACKINTOSH, OF ELIZABETH, NEW JERSEY.

PHYSICIAN'S STRADDLE-STAND.

1,308,661.

Specification of Letters Patent.

Patented July 1, 1919.

Application filed November 28, 1917. Serial No. 204,374.

To all whom it may concern:

Be it known that I, JAMES BAYARD CLARK, a citizen of the United States of America, and a resident of the city of New York, in 5 the borough of Manhattan, county of New York, and State of New York, have invented certain new and useful Improvements in Physicians' Straddle-Stands, of which the following is a specification.

10 The object of this invention is to provide a piece of furniture for use in prophylaxis and treatment of sexual infections and constructed from an anatomical standpoint so as to comfortably seat almost any sized person of either sex. A further object is to so 15 construct the stand that the patient will be brought into a position convenient to the physician for a standardized clean and correct treatment of the genital region so that 20 the parts can be thoroughly inspected and cleaned and any necessary injections or irrigations easily given with water at regulated temperature or medicated solutions. A further object is to so 25 construct the stand that the patient will not need to remove his clothes but will be forced to make adequate exposures for inspection and the proper treatment, and expeditious service will be facilitated, while 30 the clothing is completely protected from wetting or staining, as in the inspection and treatment of large bodies of troops. A further object is to bring all the paraphernalia within easy reach on the stand and laid out 35 in the order of using, whereby treatment with rapidity and accuracy is assured. A further object is to provide a piece of apparatus which will insure the confidence of the patient, impart to him a lesson in cleanliness and order, and prompt the medical 40 attendant to uniformity in treatment.

In the accompanying sheet of drawings which forms a part of this application,

45 Figure 1 is an isometric view of a straddle stand embodying this invention, and

Fig. 2 is a vertical longitudinal section.

The straddle stand comprises a bowl 3 which is provided with a table 4, and a horn 5, the horn being hollow to form an open 50 drain or trough the bottom of which slopes toward the bowl and the trough leads into the bowl. At the outer end of the horn or trough the upper edge is provided with a flange 6 which forms a convenient seat or 55 saddle which is inclined forward on which

the patient sits astride the horn. The front of the bowl on either side of the horn has concave faces which conform to the limbs of the user, and which in coöperation with the inclined seat insure his taking the proper position. The bowl, table, horn and seat are preferably a one-piece white enameled iron casting. Firm support is provided in order that a patient's weight may be sustained when he is seated at the end of the horn. 60 The form of support shown consists in securing the bowl and table portion to the wall of the room and placing under each edge a bracket 7 which is also secured to the wall, but it is not essential that the support should be wholly or partially from the wall. A drain pipe 8 leads from the bottom of the bowl, and a tap 9 rises from the table, through which water, either hot or cold or in combination may be drawn. A hot-water 75 pipe 10 and a cold-water pipe 11 lead to this tap. A flexible hose 12 is attached to the tap and terminates in a nozzle 13 of any suitable description, a rose nozzle being shown. The stand is preferably installed so 80 that the seat will be at a height of about twenty-eight inches from the floor, as this brings the patient at a convenient height for treatment by a physician of average stature, and brings a patient with average length of 85 limb nearly into a standing position and more accessible for treatment than if in a full sitting posture. The form of support is such that there is space under the horn 90 unobstructed by legs or brackets.

A patient to be treated drops his trousers and drawers, but does not of necessity remove any of his clothing, straddles the horn, sits upon the seat in a perfectly relaxed position at the end of the horn and facing 95 the bowl while still maintaining nearly an upright posture with the front side of the bowl preventing him from sliding forward from the seat onto the narrow part of the horn, and with his weight in part, depending somewhat on his stature, supported through his feet from the floor. The tops of his trousers fall under the horn. The supply of water through the pendant hose is first allowed to fall on the medical attendant's hands for washing, after which the hose is flexed to flush the genital region of the patient, and in prophylaxis a thorough soaping of the parts is followed by a running water wash. 100 105 110

What I claim, is—

1. A straddle stand provided with a bowl and a horizontally projecting horn having a seat inclined toward the bowl and the bowl 5 having faces on each side of the horn which prevent the user from sliding forward from the seat, substantially as described.
2. A straddle stand provided with a bowl and a horizontally projecting horn having a

seat inclined toward the bowl and the bowl 10 having concave faces on each side of the horn which conform to the limbs of the user and prevent him from sliding forward from the seat, substantially as described.

Signed at New York, N. Y., this 23d day 15 of November, 1917.

JAMES BAYARD CLARK.
